DESIGN FOR A GLARE SIGNAL FOR AUTOMOBILES

Mate Angelich, Jackson Heights, N. Y.

Application August 15, 1941, Serial No. 102,853

Term of patent 14 years

To all whom it may concern:

Be it known that I, Mate Angelich, a citizen of the United States of America, residing at Jackson Heights, L. I., in the county of Queens and State of New York, have invented a new, original, and ornamental Design for a Glare Signal for Automobiles, of which the following is a specification, reference being had to the accompanying drawing, forming part thereof.

Figure 1 is a face view of a glare signal for automobiles embodying my new design.

Figure 2 is an edge view of the same looking from the right hand side of Figure 1.

I claim:

The ornamental design for a glare signal for automobiles, as shown.

MATE ANGELICH.
